UNITED STATES PATENT OFFICE.

GARRETT E. MILLER, OF WEST NYACK, NEW YORK, ASSIGNOR TO LOCOMOTIVE SUPER-HEATER COMPANY, OF NEW YORK, N. Y., A CORPORATION OF DELAWARE.

FLUE-TUBE SUPERHEATER.

1,199,405.

Specification of Letters Patent. Patented Sept. 26, 1916.

Application filed September 14, 1915. Serial No. 50,568.

To all whom it may concern:

Be it known that I, GARRETT E. MILLER, a citizen of the United States, residing at West Nyack, Rockland county, State of New York, have invented certain new and useful Improvements in Flue-Tube Superheaters, of which the following is a specification.

My invention relates to superheaters of the type employing tubes inserted in some or all of the flue tubes of a flue tube boiler, said tubes being connected at their ends to suitable main pipes or collecting chambers in such a way that saturated steam passes from the boiler through the tubes, where it is superheated, to the steam chests of the engine. The flue tubes employed to hold the superheater may be of normal size or may be enlarged, as the case may be. Superheaters of this type are largely used for locomotive and marine work and also find considerable application in stationary boiler and engine practice.

It is the object of my present invention to provide a superheater, of the class referred to, with a novel arrangement of collecting headers with reference to which the superheater tubes or elements may be attached or detached conveniently, quickly and easily.

A further object of my invention is to provide such an arrangement of headers and superheater elements as will require but a single shape of superheater element so that any element may be placed in any flue tube. This makes for speedy manufacture and economical construction as well as for economy in repairs, inasmuch as but one style of superheater element need be carried in stock.

A further object of my invention is to provide an arrangement of superheater headers in which the unequal expansion of the saturated and superheated headers, due to the diverse temperatures of the contained saturated and superheated steam, and the unequal expansion of the superheater collectors and elements as compared with that of the boiler shell from which said parts are supported, shall not exert any injurious strains upon the header structure.

Still a further object of my invention is to provide a novel form of element end and associated clamping arrangement by means of which the elements may be quickly attached to and detached from the headers and the joints between headers and element

ends may be made steam tight and maintained tight despite the jars of operation and the strains induced by changing temperatures.

Other objects of my invention will appear as the specification proceeds.

My invention will be better understood by referring to the accompanying drawings in which—

Figure 1 represents a central sectional elevation (along the line 1—1 of Fig. 2) through the smoke box end of a locomotive boiler provided with a superheater according to my invention; Fig. 2 represents a view taken from the right of Fig. 1; Fig. 3 represents a section, enlarged, taken along the line 3—3 of Fig. 1; and Fig. 4 represents a section along the same line as Fig. 3, but still further enlarged, so as to show the detailed construction of the element ends and of the clamping means which attaches them to the header branches.

In the drawings, the boiler, 1, having the usual front tube sheet, 2, the normal diameter flue tubes, 3, and enlarged flue tubes, 4, is further provided with a header, 5, arranged in the smoke box, 6, in front of the flue tubes. This header comprises a pair of transverse collecting chambers, 7, and, 8, for saturated and superheated steam respectively, extending across the boiler above the smoke tubes. The saturated chamber, 7, is supplied with steam through a bent inlet pipe, 9, which is connected, in the usual way, at the front tube sheet to a pipe, 10, leading from the steam dome of the boiler. Similarly the superheated steam chamber, 8, is provided with a pair of laterally disposed pipe connections, 11, 11, to which are joined pipes, 12, leading to the two steam chests (not shown). The two collecting chambers, 7, and, 8, with their inlet and outlet pipes, 9, and, 11, constitute, with the header branches now to be described, an integral one piece structure.

Opening from the collecting chambers, 7, and, 8, and extending vertically downward between alternate vertical rows of enlarged flue tubes are header branches, 13, and, 14, for saturated and superheated steam respectively. These branches are preferably parallel sided and have smaller dimensions, taken across the boiler than in the length of the boiler; they are arranged in pairs with the superheated branches in front of the

saturated branches. Each superheated and saturated header of a pair is connected together, at a point just above the top row of flue tubes but below the collecting chambers 5 by a solid yoke, 15.

There is one superheated element, 16, to each enlarged smoke tube; this element comprises four tube lengths laid side by side and joined in series by return bends in the 10 usual way. The free ends, 17, and, 18, of each element are brought out one above the other and bent slightly toward the axis of the flue tube as they emerge therefrom. One of the ends is left substantially straight, 15 while the other and longer end is bent slightly away from the axis of the other end.

The free ends of the element ends are provided with heads, 19, for attachment to 20 the header branches. These heads are hollow and may be cast or forged. Each head has an opening at one end into which the pipe end is welded and a spherically formed side in which is another opening adapted to 25 connect with a corresponding spherical opening in the header branch. The opposite side of the head, 19, is provided with a spherically tipped boss or projection, 20.

A single clamp is used for attaching both 30 ends of a single element to the two headers. This clamp comprises a linear bar, 21, having a central opening through which is inserted a bolt, 21', which is also inserted through the space between the front and 35 rear headers of a pair and the head, 22, of which is locked in recesses provided by lugs, 23, formed upon the sides of the headers, whereby the bolt is prevented from turning. Each end of the clamp is provided with a 40 recess in which is seated the boss, 20, of the head 19. Nuts, 24, threaded upon the end of the bolt, force the spherically formed sides of the heads into steam tight engagement with the similarly formed openings of the 45 headers.

As previously stated, the shape of each element is like that of every other element. Those elements belonging to the flue tube which lies immediately to the left of a pair 50 of header branches (as viewed from Fig. 2) have their longer ends below the center of the flue tube and extending downwardly from rear to front; the clamp bar, 21, therefore, also extends downwardly from rear to front. Those elements belonging to the flue tubes immediately to the right of any pair of header branches are reversed, with respect 55 to the elements to the left as just described, i. e., the elements are rotated axially through 60 180°. The longer ends of each element, therefore, are now above the center of the flue tube and are bent forwardly and upwardly and the clamp members similarly extend upwardly from rear to front. It will 65 be seen that the above arrangement brings

the two bolts, 21, belonging to the two elements at the right and left of a header branch, one above the other so that neither interferes with the other but is quite independent thereof. Any individual element 70 may, therefore, be removed and repaired or replaced at any time without disturbing any other element.

Both the collecting chambers, 7, 8, and header branches 13, 14, being spaced away 75 from one another and there being no physical connection between the saturated system (collecting chamber, 7, and header branches, 13,) and the superheated system (collecting chamber and header branches 14) except 80 that of the narrow sectional yoke, 15, there is but little loss of heat from the superheated to the saturated system, and, for the same reason, the parts of the saturated system, and of the superheated system, which are at different temperatures, are free to expand and contract independently and no injurious strains are set up in the header structure because of said different temperatures. Furthermore, by reason of the yoke, 15, being 85 below the collecting chambers but above the flue tubes, the two collecting chambers as well as the members of each pair of header branches may be displaced, through reasonable limits, with reference to one another, 90 the yoke, 15, serving as a pivotal axis for such displacement. Forces tending to so displace the collecting chambers arise not only by reason of the temperature differences between saturated and superheated steam but also because of the fact that the outlet pipes, 11, which are rigidly joined to the superheated collecting chamber, are supported from a part of the boiler mounting 95 which remains much cooler than the collecting chambers themselves or than the inlet pipe, 9, joined to the saturated collecting chamber. And forces tending to so displace the header branches arise because of the fact 100 that each superheated element end assumes 105 a much higher temperature than the corresponding saturated end so that the header branches are forced apart for increased production of superheated steam and drawn together for decreased production of superheated steam. 110

The flue tubes which contain superheater elements, being at the sides of the header branches, are very accessible for cleaning, and the clamps and element ends being directly in front of the flue tubes, any superheater element may be drawn straight forward for repair or replacement and will not be interfered with by any other element or by any part of the header structure. 115

In special cases the header structure may be strengthened by joining a detachable link between the lower portions of the several pairs (saturated and superheated) of header branches. These links should be so attached 120

that each branch is free to shorten or lengthen vertically without transmitting strain to the link or to the other branch.

Having described my invention, I claim:

- 5 In a flue tube boiler provided with a superheater header having pairs of superheated and saturated header branches, one in front of and spaced from the other, between alternate vertical rows of flue tubes, said
- 10 branches having lateral openings, superheater elements in some of the flue tubes, heads on the ends of each element each head having a spherically shaped side and an

opening therethrough and on opposite side having a spherically tipped boss, the openings of a pair of ends being in registry with openings in a pair of header branches, a clamp bar having end recesses to receive the spherically tipped bosses, and a bolt passing between the branches and through the center 20 of the clamp bar for holding the element ends fast.

In testimony whereof I have hereunto set my hand.

GARRETT E. MILLER.
